UNITED STATES PATENT OFFICE.

WILLIAM HARRY KESSLER, OF JAMESTOWN, INDIANA.

DESIGN FOR AN AUTOMOBILE-TIRE.

46,772.

Specification for Design.

Patented Dec. 15, 1914.

Application filed December 19, 1912. Serial No. 737,737. Term of patent 14 years.

To all whom it may concern:

Be it known that I, WILLIAM HARRY KESSLER, a citizen of the United States, residing at Jamestown, in the county of Boone and State of Indiana, have invented a new, original, and ornamental Design for Automobile-Tires, of which the following is a specification, reference being had to the accompanying drawing, forming part thereof.

Figure 1 is a plan view of a portion of the

tread. Fig. 2 is a sectional view taken on line 3—3 of Fig. 1.

I claim:

The ornamental design for an automobile tire as shown.

WILLIAM HARRY KESSLER.
